United States Patent

Des. 240,702
Patented July 27, 1976

240,702

ELECTRIC CAN OPENER

Robert J. Scott, Blue Springs, and Bill G. Mead, Raytown, Mo., assignors to Rival Manufacturing Company, Kansas City, Mo.

Filed Mar. 20, 1975, Ser. No. 560,253

Term of patent 14 years

Int. Cl. D7—99

U.S. Cl. D8—36

Fig. 1.

Fig. 3.

Fig. 2.

Fig. 4.

Fig. 5.

Fig. 6.

Fig. 7.

Fig. 8.

FIG. 1 is a perspective view showing the front and left side views of the electric can opener;

FIG. 2 is a front elevational view thereof;

FIG. 3 is a left side elevational view thereof;

FIG. 4 is a right end elevational view thereof;

FIG. 5 is a rear elevational view thereof;

FIG. 6 is a top plan view thereof;

FIG. 7 is a bottom plan view thereof; and

FIG. 8 is a perspective view similar to FIG. 1, but showing the rear and opposite side of same.

We claim:

The ornamental design for an electric can opener, as shown and described.
